ADOLF KUCHARZIK, OF BERLIN, AND ARNO SCHMIDT, OF BERLIN-CHARLOTTENBURG, GERMANY

RELATIVELY STATIONARY BODY WITH A SINGLE PUNCTIFORM OR APPROXIMATELY PUNCTIFORM SUPPORT OR A PLURALITY OF SUCH SUPPORTS IN ONE ROW

Application filed November 30, 1926, Serial No. 151,750, and in Germany December 3, 1925.

Our invention relates to conveyances or vehicles provided with punctiform or approximately punctiform supports and means for stabilizing the same.

It is well known that a circular body rotating at high speed about its own axis will maintain its balance in apparent contradiction to the laws of gravity in any plane within which it rotates. This is, for instance, the case in the gyroscope. Thus, for example, a gyroscope rotating within an envelope, may maintain its balance upon one corner of said envelope. Furthermore, the gyroscope may be made to travel along a stretched cord upon this corner of the envelope without disturbing its balance. Thus, notwithstanding the presence of the envelope, the gyroscope has only a single point of support.

It is also known that a relatively stationary body which is provided with two points of support arranged in a line, can be maintained in equilibrium by a proper balancing of the weight above one of the supporting points, as, for example, in a bicycle.

Another solution of this problem of balancing relatively stationary bodies having one or more punctiform or approximately punctiform supports, is accomplished according to our invention, by a rotating device which produces a whirling or eddying of the air for securing a proper balance of the relatively stationary body. Thus, for example, a suitable whirling of the air may be produced by one or more blades or vanes rotating clockwise or anti-clockwise. The rotating blades or vanes may, for example, be designed similarly to the propellers in airplanes or in a manner similar to the vanes or wings of wind or other turbines. It is furthermore possible to balance a monorail or line-supported vehicle by means of two or more pairs of blades rotating in opposite directions and suitably mounted so as to be adjusted to any desired plane of revolution between the horizontal and vertical planes. It thus becomes possible to provide a vertical component sufficient to retain the vehicle in upright position as hereinafter explained in connection with Figure 8 of the drawings.

The body, to be maintained in balance, may

be provided with additional rotating planes on opposite sides of the plane containing its points of support. The planes of rotation may be inclined to any desired angle, for example, by the use of ball and socket connections with the shafts which drive said rotating planes.

The blades which produce the whirling of the air should have a speed which corresponds approximately with that of the aeroplane motors. By means of the rotating blades, air is drawn in between the relatively stationary body and said blades. Those portions of the relatively stationary body which are disposed opposite to the blades, should therefore be given a shape or configuration suitable for sucking in the air.

The supports of the relatively stationary body or vehicle may consist of wheels, rollers, slide rails or runners. Said vehicle supports are then arranged and adapted to travel on substantially punctiform or monorail supports.

It has heretofore been proposed to propel a stabilized vehicle along double rails by the whirling of air, but according to our invention, it becomes possible to utilize the whirling of air not only for the propulsion of a monorail vehicle or the like but also for the maintenance of said vehicle in balance or equilibrium. This object may be attained by means of blades or vanes arranged at the ends of the relatively stationary body. The relatively stationary body may thus be drawn forward in a direction corresponding to the direction of travel at any particular instant. The propeller located in the rear of the body, may be rotated in the same direction as the propeller in front or may remain stationary. For maintaining balance special propellers may be provided to operate in horizontal or vertical planes as well as in planes intermediate thereto.

The maintenance of proper balance may also be accomplished by one and the same air whirling device or propeller operating in a horizontal plane adjacent to the front but capable of being arranged in a position in which it operates in a plane deviating from the horizontal. The force K acting under an

angle to the plane is then resolved into its components F and H, as illustrated in Fig. 8 of the drawings. It will be understood that the component H can be made to exert such a strong upward pull that the body 11 of the vehicle may in effect be practically suspended in such a way as to counteract the tilting effects. Component F is then available for propelling the vehicle and for regulating its speed. If the weight of the vehicle is so great as to render it impossible to thus counteract the tilting effects while at the same time maintaining a sufficiently large component F for propelling the vehicle, it becomes necessary to employ the laterally-presented propellers 16 and 17 as shown in Figure 9 for maintaining equilibrium.

If the whirling of the air takes place in the horizontal plane a tractive force at right angles to the plane of rotation of the propellers is generated which more or less relieves the supports of the weight of the relatively stationary body, depending upon the intensity of the whirling action. In this way the weight of the conveyance is partly supported by the whirling of the air, thereby reducing the friction at the supporting points. It will be possible to form an idea about this if it is assumed that the supporting points consist of wheels which run along a rail or a railless road.

Heretofore, it has been necessary to make the weight of the driven relatively stationary body as large as possible since upon this and the friction depended the weight of the train to be hauled.

Inasmuch as the driving of vehicles by air-displacing propellers may be made to more or less counteract the effect of gravity, it follows that the weight of the vehicle need not be any greater than is required to impart the necessary mechanical strength and carrying capacity.

Where the revolving elements are arranged in vertical planes such as on opposite sides of the balanced relatively stationary body, it becomes possible to relieve the supports from lateral pressure. The advantage of this arrangement will be best understood in connection with a vehicle traversing a curve, as illustrated in the Figures 18 to 28. Heretofore, the centrifugal force acting upon a vehicle rounding a curve has been compensated by elevation of the outer rail, thus preventing an overbalancing of the relatively stationary body on a curve. In this way, however, a pressure is generated which acts upon the elevated track from the center of curvature.

According to our invention centrifugal force upon a curve is compensated for by additional rotating planes acting at right angles to the supports and thus partially or entirely taking up the lateral pressure due to centrifugal force. This compensating may

be regulated automatically by any suitable well-known type of governor which is connected up to the motor which drives the propeller which is thus adapted to vary the lateral pressure in the manner hereinafter pointed out in connection with Figures 18 to 28 of the drawings.

This whirling of the air may be effected by means known per se, as already mentioned, by propellers or turbine wheels.

The present invention also contemplates the use of wind wheels suitably disposed above the relatively stationary body in such a way that they are not exposed to the wind pressure on the straight track, but upon a curve are brought into position to be acted upon by the natural force of the wind so that the pressure produced by the vehicle travel counteracts the centrifugal force.

The rotary blades may be driven by a prime mover, such, for example, as a high speed internal combustion motor. If desired, a variable speed transmission device may be employed for operating the rotary blades at any desired speed by any suitable motor. This motor may also be employed for driving the wheels of the vehicle.

The drive for the rotating blades may also consist of one or more motors arranged at the wheels so that the surplus power not required for the wheels by reason of the reduced friction, may be employed for driving the propeller blades through any suitable transmission device.

As hereinafter explained, the vehicle supports may consist of the rotating parts of special motors mounted at the wheels. For example, the rotor of an electric motor may be designed as a supporting runner wheel. Such runner wheels should be journaled in suitable manner to dampen vibrations and absorb shocks caused by the track.

When the vehicle comes to a stop further means would have to come into operation for maintaining the balance. In the case of a sudden stoppage of the drive a failure of the air whirling fans on the forwardly-moving vehicle would throw said vehicle out of equilibrium, thus causing it to fall.

According to our invention this is prevented by the provision of suitable balancing supports for the vehicle. These supports are preferably arranged symmetrically on opposite sides of the running supports, a device which is responsive to the speed of the propellers being arranged to position these supports in readiness to operate whenever the normal speed of the driving motor drops to such a degree that the vehicle is not maintained in balance by its forward movement. The points of the supports may likewise be equipped with wheels, runners or rollers. They may, for instance, rest upon rails located upon opposite sides of the supporting points of the vehicle.

The side supports may at the same time be designed as brakes. The braking action may be effected automatically by the vehicle wheels, for example, when the propellers are no longer operative or have been stopped. 5 Inasmuch as the supporting points of the side supports are located lower than the supporting points of the vehicle body, the former take up almost the entire weight of the vehicle. 10

The side rests should then be brought into such a position that they form an angle with the track or runway, in order to absorb the pressure generated during their application according to the direction and speed of travel. These side rests also serve to support the vehicle body when it has come to rest. 15

Where the conveyance is intended for the transport of people or goods along a single rail or a trackless road, all the well-known devices employed for braking, propulsion, reducing resistance of the air and equipment, may be employed. 20

In the drawings affixed hereto some embodiments of our invention are illustrated 25 by way of example.

Figure 1 is a diagrammatic side elevation of one embodiment of our invention.

Figure 39 is a detail of a preferred form of motor for driving a vehicle equipped with our invention.

Figure 40 is a front elevation of one of the wheel supports detached. 70

Figure 41 is a front elevation of a modified form of the wheel support.

Fig. 1 of the drawings illustrates the general principle underlying our invention, a relatively stationary body 11 being maintained in stabilized equilibrium upon a punctiform support 12 by means of revolving propeller blades 13. Housed within the body 11 is a suitable device for driving the blades 13, which may thus be revolved at sufficient speed to practically counteract gravity effects and thus prevent tilting. 75 80

According to the same principle in Fig. 2, a vehicle body 11 is provided with wheels 14 adapting it to be propelled by any suitable means along a single rail 15. 85

Fig. 3 shows an end elevation of Fig. 2, the wheels 14 running on the rail 15 being provided with double flanges. Said wheels 14 rotatably support the relatively stationary body 11 while the propellers 13 are mounted on top of the carriage, as in Figs. 1 and 2. The dotted line shows a special shape or configuration of the parts of the relatively stationary body 11 adjacent to the blades which may be barrel-shaped, dome-shaped or arched so that a funnel-shaped suction chamber is formed between the blades 13 and the curved top of the body for the intake of air under a strong draft and a forcible ejection therefrom in a whirl. 90 95 100

Fig. 4 of the drawings is a top plan view of Figs. 2 and 3 to show the construction of the planes as viewed from above. The blades may be designed to form a single or double propeller. Any desired number of blades may be arranged above one another in the manner of propellers. The blades rotate either clockwise or anticlockwise. 105

In Fig. 5 of the drawing the relatively stationary body 11 is equipped with blades 13 operating in a horizontal plane and with blades 16 and 17 operating in vertical planes parallel to a straight line connecting the supporting points of the wheels. The object of the blades 16 and 17 located in the vertical plane will be more fully explained below. 110 115

Fig. 6 is an end view of Fig. 5, showing in dotted lines the preferred cross section of the body. 120

Fig. 7, is a top plan of Fig. 6.

According to the embodiment of my invention shown in Fig. 8, the planes 13 normally operate in horizontal planes but may be adjustably positioned in both directions as indicated by arrows to operate in different inclined planes as indicated in broken lines. In the diagram shown on the left of this figure the force K generated by the propeller blades 13 may be resolved into two compo- 125 130

ments, the vertical component H serving to maintain the balance and the horizontal component F acting to propel the vehicle along the rail 15. It will be understood from this description that by a suitable adjustment in the angle of inclination of the propeller, these components may be increased or reduced with respect to each other so that in the horizontal position of the propeller the force F may become zero and the body remain at rest. By inclining the propeller planes towards the vertical the force F is increased so that the body may be started slowly and gradually accelerated as the blades approach their vertical planes of movement so that a regulation of the speed of the vehicle may thus be effected. In this way, by the time the rotating plane reaches a vertical position, the body has attained its maximum speed and the force H becomes zero. At the same time, the horizontal component H may be governed in such a way as to counteract the tilting effects on a running vehicle, either by itself alone where the weight of the vehicle is not too great, or in conjunction with laterally-presented air-propellers when the weight of said vehicle is excessive.

Fig. 9, shows an end elevation corresponding with Fig. 8, the propeller shaft 18 being adapted to move in a slot 19.

Fig. 10, is a top plan of Fig. 9.

In Fig. 11 of the drawing a plurality of blades 13 arranged above the ends 20 and 21 of the car, may be moved from a horizontal plane into vertical transverse planes at opposite ends of the car when the blades 22 operating in a horizontal plane at the middle of the body take over the balancing. The blades 22 in the middle revolve about a fixed axis while the blades 13 at the ends 20 and 21 revolve in the same direction and in this position assist each other in propelling the car. It will be understood that by a suitable regulation in the direction of rotation of the blades 13 at any particular time, it becomes possible to drive the car forwards or backwards. The ends 20 and 21 of the relatively stationary body are suitably formed as described above to suck in the air in any position of the rotating blades.

Fig. 12 of the drawings shows by way of example a preferred cross-section for the central portion of the car body with respect to the blades according to the embodiment shown in Fig. 11.

In Fig. 13 is illustrated one end of a conveyance provided with four points of support, arranged to provide a duplex point support at each end of a vehicle. If the relatively movable body is a railroad car, these supports may form bogeys. The blades 13 at the ends 20, 21 of the car may be adjusted between vertical and horizontal planes or be mounted to revolve about fixed axes. In the latter case, the speed of the vehicle is

varied by altering the speed of the blades. The ends of the vehicle are preferably formed as shown in the drawing. In this case a plurality of blades 22 are provided in the middle of the vehicle, said blades being preferably revolved in opposite directions for maintaining a proper balance.

Fig. 14 is a top plan of Fig. 13.

Fig. 15 illustrates a further embodiment of our invention in which the vertical blades are replaced by a plane 24 located above the vehicle and rotatable around a shaft 23 which forms a continuation of the turning axis of the bogeys. This plane 24 as shown in Fig. 16 is so placed that when the vehicle travels in a straight line it offers no resistance. When travelling along a curve, however, said plane is turned either by the angular motion of the bogey or by some other controlling device operating according to the direction of the wind to produce a force which counteracts the centrifugal force which may be created at any particular instant. For simplifying and facilitating the turning of this blade during high wind velocities the plane 24 may be provided with a Flettner rudder or any other suitable device. It is also contemplated to arrange propeller blades between the roof of vehicle 11 and the plane 24 for which purpose the propeller shaft may be made hollow to permit the passage therethrough of the shaft for adjusting the plane 24. Plane 24 may be suitably mounted to be tilted from its horizontal position.

In Fig. 17 is illustrated an electrically operated vehicle which is fed with current from the trolley lines 25 by means of sliding collectors 26. The equipment which was used for the test runs of the electric high speed railway track Lichterfelde-Zossen and gave great satisfaction at speeds up to 220 km. per hour may be employed here. It will be understood, however, that the rail or rails 15 can be employed for the supply of electric current. This vehicle is provided with six axles and has the characteristics fully described with reference to the preceding figures of the drawings. The front and rear ends 20 and 21 are suitably shaped to reduce the resistance of the air.

The manner of employing the several embodiments illustrated in the drawings will now be readily understood.

The relatively stationary body, for instance, may be conceived as a vehicle travelling along a single rail in the manner of a monorail railway. It is also possible to employ such a vehicle as a single track automobile by designing one of the supporting points as a steering device. By the rotation of the blades the vehicle may be balanced without in any manner disturbing the steering capacity of the relatively stationary body. The revolving blades by whirling the air produce an effect similar to a gyroscope. They have the ad-

vantage over the gyroscope that they are comparatively light and if driven with sufficient power may relieve the supports or wheels of part of the load so that some of the weight of the vehicle is taken from the axles.

By making use of the revolving blades for propelling a vehicle, said vehicle can be made to attain a very high speed. This speed would, however, be limited by the curves in the track which are unavoidable in any railroad. This limit is set by the magnitude of the centrifugal force.

To adopt the hitherto proposed solution of the problem of the centrifugal force in curves by raising one of the rails would be impossible at such speeds on account of the excessively large angle required.

According to our invention we therefore provide blades, vanes or revolving planes 16 and 17 in a vertical plane parallel to the direction of motion of the vehicle and thus by the force produced, compensate the centrifugal force. As already mentioned these blades may be replaced by blades capable of angular motion and operating as follows:

According to Figs. 18 and 19 curves are drawn to illustrate diagrammatically, the behavior of a relatively stationary body when provided on opposite sides with revolving blades 16 and 17 arranged in planes parallel to the direction of travel. The blades or vanes 13 working in the horizontal plane are here omitted for the sake of clearness. The laterally-spaced blades arranged on opposite sides of the car, are here made to rotate in opposite directions to each other and revolve idly at times when said car is traveling over a straight track. When, however, a curve is reached, they act automatically and at right angles to the track forces to generate a stronger force (g) directed towards the center of the curvature and a force (z) directed away from the center of curvature, which is practically nihil. During a straight line travel these forces g and z balance each other, as shown in Figs. 20 and 21. The force in the direction of travel is indicated by the line v .

During travel around a curve, the forces z (additional force) and g (counter force) are not equal to each other as they are during a straight-away course but on the contrary, their relative magnitudes are altered to correspond to the centrifugal force developed on the curve so that the representation of the forces are shown in Figs. 22 and 23.

According to Figs. 18 and 22 the counter force g produced by the rotation plane 17 acts towards the center of curvature and compensates for the centrifugal force c as well as for the force z produced by the rotation plane 16 in a direction away from the center of curvature. The centrifugal force c developed on the curve is therefore counter-

balanced. The force v acting in the direction of travel therefore remains unchanged.

The Figures 19 and 23 show an inversion of the same condition.

It is of importance to consider the forces acting on the top surface of the rail.

In Fig. 24 are illustrated the effects due to an ordinary vehicle running on two rails, the center of curvature being located on the left. The outer radius is indicated by the letter r_a and the inner radius by the letter r_i . Let it be assumed first that the outer rail is not raised. The centrifugal force c acts towards the right and forms with the weight G of the vehicle (assumed to be concentrated at point m) the resultant force R which tends to overturn the vehicle in a clockwise direction about the outer rail.

In Fig. 25 similar effects are shown when the outer rail is elevated, the resultant R in this case acting normal to the rail base to counteract the overturning tendency of the centrifugal force c .

Figs. 26, 27 and 28 illustrate graphically the forces involved according to the present invention. With a center of curvature located on the left, the radius of curvature of the single rail may be represented by r . The weight of the car G rests in the center line of the rail 15. The centrifugal force c developed acts towards the right. To the centrifugal force c is added in like manner to that shown in Figs. 19 and 24 an additional force z . These two forces may be counterbalanced by the force g created by rotary vanes 16 so that no resulting force is developed and only the weight of the car less the force H developed by the rotating blades in the horizontal plane presses upon the rail.

According to the polygon of forces illustrated in Figure 27, the weight G of the vehicle applied at point m may be represented by the line $m-G$. In the same way, the centrifugal force c operating upon the vehicle may be represented by the line $m-c$. The force z exerted by the relatively slow running lateral propeller is in the same direction as the centrifugal force and may be represented by the line $c-z$. Counteracting these combined forces, is the force g exerted by the relatively fast-running lateral propeller which may be represented by the line $z-g$. The resultant R of these forces may then be represented by the line $m-R$ acting normal to the rail base, the horizontal component U ($R-G$) of weight G being exerted toward the left and closing the force polygon.

As indicated in the upper left-hand portion of Figure 27, the lifting force H operates oppositely to and in line with resultant R , said force H being that exerted by an upwardly-presented air-whirling wheel. This force H may be resolved into a vertical component N counteracting the weight of the ve-

hicle and a horizontal component S counteracting the centrifugal force on a curve.

The combined effects of all of these forces may be represented in a closed polygon as shown in Figure 28. Thus force H may be taken as a counterpressure to resultant R , giving a net resultant represented by the line $m-H$. Likewise vertical component N in effect reduces the gravity effect of the vehicle 10 while the horizontal component S may be taken in counteraction to the centrifugal force. In effect therefore with respect to the forces acting upon the vehicle, we have the closed force polygon referred to the point m as follows. Centrifugal force $m-U$, horizontal component S , net gravity effect $S-H$, and net rail reaction $H-m$.

When travelling along a straight track the forces z and g will in case of a strong wind 20 pressure upon the side faces of the vehicle not be equal as in Figs. 20 and 21, but that blade which is opposite the wind pressure will produce a stronger force than the other blade and will take up the wind pressure so 25 that no upsetting torques can be developed.

It is thus theoretically possible to traverse the curves almost without friction since a lateral pressure is not exerted upon the rails by the centrifugal force. The rolling friction is, 30 as described above, also reduced to a certain extent by the force H of the horizontal rotating plane so that only the friction due to steering the vehicle around the curve, has to be overcome.

35 The centrifugal force itself is also reduced by the reduced weight of the mass which, as hereinbefore mentioned, is no more than that required by the carrying capacity of said vehicle. In the equation

$$40 \frac{\text{mass} \times \text{velocity}^2}{2} = \frac{m \times v^2}{2} = \text{kinetic energy}$$

the mass m becomes smaller and thus also the centrifugal force.

45 There is furthermore a decided advantage to be secured on curves by vehicles which run at high speeds upon a single rail.

As is generally known, two wheels upon the same axle are forced to rotate at different speeds when negotiating a curve resulting in a twisting of the axle or skidding of one of the wheels. To overcome this difficulty in motor cars, differential gears must be provided. In railway vehicles coaxial wheels are 50 rigidly secured to one axle and thus combined into a unit which makes it impossible for said wheels to rotate at different speeds. This fact explains one of the principal causes 55 for the derailment of railroad cars when traversing a curve at a speed which exceeds that for which the elevation of the outer rail has been determined. This drawback is not present in a monorail vehicle because there is 60 only one radius for a single wheel. This mo-

mentum may also be eliminated by composing the runner wheel, as shown in Fig. 41 of two parts 49 and 50 so that the two axles 48 or 51 are capable of being rotated differentially.

A vehicle travelling upon a single rail is naturally exposed to the danger of overturning in case of a sudden stoppage of the air-whirling vanes.

According to our invention this difficulty 75 is avoided by providing supports at opposite sides of the relatively stationary body 11 or the vehicle, as shown in Figs. 29 to 38, said supports being adapted to assume a position of readiness to become operative when 80 the speed of the drive drops to a noticeable extent and the balance can no longer be maintained by the propellers.

According to Figs. 29 and 30 and the corresponding side-elevations shown in Figs. 31 85 and 32, vertically-movable supports comprise vertical rods 27 provided with wheels or rollers 28 adapted to run upon rails 29 and 30 arranged on opposite sides of the running rail 15. Said supports may be provided with 90 lateral stays 31 and 32 for counteracting the speed pressure and in case these side supports are also employed for braking the vehicle they may be made to operate as brake rods between the rail and supporting platform of the vehicle. The supports rest completely upon the rails when the drive fails entirely, and as shown in Figs. 29 and 31, support and balance the relatively stationary 95 body.

In the embodiment illustrated in Figs. 30 and 32 the rods 27 are adapted to be drawn into or close to the body of the vehicle so as not to interfere with the propulsion of the vehicle. The rods 27, 31 and 32 may be 100 designed as racks and be operated by any usual means.

The embodiments shown in Figs. 33 and 35 have simple supports 33 pivoted upon the side walls of the vehicle which in operative 105 position form an angle with the vertical and balance the vehicle.

In Figs. 34 and 36 their position during the travel of the vehicle is shown. They are then drawn up along the sidewalls 34. The points of contact 35 of the supports 33 are fitted with caterpillar chains in the manner of tanks and mounted upon the supports 33 by means of ball-bearings so that obstacles along the track may be readily overcome. 110 The upper ends of supports 33 are provided with roller bearings or pinion and rack connections arranged in recesses of the sidewall 34, thus enabling said supports to absorb the shocks. A suitable device is provided for 115 depressing the rods 33 to the ground whenever the balance has been lost. The guide rollers 38 and 39 on the frame of the vehicle are also flexibly coupled so that a proper constraint is ensured thereby. These sup- 120

ports 33 may also be suitably stayed to resist the travelling pressure developed when placed upon the ground.

In the embodiment illustrated in the Figs. 37 and 38 the supports consist of stayrods 40 and 41 and a roller 42 on each side capable of moving along guide rails 43. The stays 40 and 41 in this case, not only serve as brake rods but also as stiffeners for the framing of the car.

All these supports may be automatically controlled by the driving motor of the propellers so that the following effect is obtained, as mentioned above. In travelling position, the supports are drawn up, as shown in the Figs. 30, 32, 34, 36 and 38. After the speed of the motor has dropped somewhat, said supports are brought to positions of readiness for action without hindering the movement of the car. Only when the speed drops so low that the vehicle no longer balances do said supports come into positions to support or brake the vehicle. The fall of the car is thus effectively prevented. These positions of the supports are shown in Figs. 29, 31, 33, 35 and 37.

It will be understood that the supports may be suitably designed to give the best results in each individual case.

The propellers may be surrounded by protective wire nettings which allow only the air to pass but prevent the entry of solid bodies between the blades.

In the embodiment illustrated in Fig. 39 the rotating part of the motor is designed as runner wheel 44 in such a way that the motor windings are located at the right and left of the runner wheel 44 in casings 45 and 46 which are mounted upon the bogeys or underframes of the vehicles by means of rods 47. The axle 48 may be journaled in these casings or separately.

In the embodiment illustrated in Fig. 40 the runner wheel consists of a single piece while in that illustrated in Fig. 41, it is composed of two parts 49 and 50. A hollow axle 51 is capable of turning upon the axle 48 to a certain extent. This device provides, as already described, the means to enable the two parts of the runner wheel to run with different speeds due to the different radii of curvature of the running wheel face.

In order to reduce friction even at high speeds, all bearings are provided with forced lubrication so as to avoid overheated bearings.

In carrying out our invention according to Figs. 29 to 32 and 37 and 38, it becomes possible to adapt all railroad tracks with two rails for vehicles constructed according to our invention without disturbing the ordinary service. Thus by inserting a third rail with an elevated surface between the other two rails, the double track system may be converted to our improved system while at

the same time providing a third rail for the electric current.

Either individual motor cars may be employed or trains may be composed of such carriages.

Various changes and modifications may be made without departing from the spirit and scope of our invention which we desire to claim in the broadest possible terms consistent with the prior state of the art.

We claim:

1. A relatively stationary body with one or more substantially punctiform under supports, in combination with balancing apparatus including an air whirling device.

2. A conveyance body provided with one or more substantially punctiform supports, in combination with balancing apparatus including one or more blades adapted to revolve clockwise or anti-clockwise.

3. A conveyance body provided with one or more substantially punctiform supports, in combination with balancing apparatus comprising two or more pairs of blades rotatable in opposite directions.

4. A conveyance body with one or more substantially punctiform supports, in combination with balancing apparatus including two or more pairs of blades rotatable in opposite directions in substantially horizontal planes.

5. A conveyance body provided with one or more substantially punctiform supports, in combination with balancing apparatus including two or more pairs of revolable blades presented in opposite directions and operating in vertical planes transverse to a straight line connecting the supporting points.

6. A conveyance provided with one or more substantially punctiform supports, in combination with balancing apparatus consisting of two or more pairs of blades revolvable in opposite directions and in planes parallelly and transversely disposed with respect to a straight line connecting the supporting points.

7. A conveyance provided with one or more substantially punctiform supports, in combination with balancing apparatus consisting of two or more pairs of blades adapted to revolve in opposite directions in planes arranged horizontally parallel, vertically transverse, and vertically parallel with respect to a straight line connecting the supporting points.

8. A conveyance provided with one or more substantially punctiform supports, in combination with a balancing apparatus consisting of two or more pairs of blades revolvable in opposite directions on axes movable between horizontal and vertical planes.

9. A conveyance provided with one or more substantially punctiform supports, in combination with balancing apparatus comprising

- two or more pairs of blades revolvable in opposite directions, and other blades revolvable about axes inclined to a line connecting said punctiform supports, the planes within which said blades revolve being suitably arranged with respect to the outer wall of said conveyance to induce a suction of air towards said blades.
10. A vehicle body supported on wheels arranged in a plane in combination with balancing apparatus consisting of suitably located propeller blades.
11. A vehicle provided with carrying wheels arranged in a common plane in combination with balancing apparatus comprising air whirling devices located at the ends of said body.
12. A vehicle supported on wheels arranged in a common plane, in combination with balancing apparatus comprising air whirling devices at the ends of said vehicle, said air-whirling devices being adjustably mounted for producing variable components of active force for respectively balancing and propelling said vehicle.
13. A conveyance provided with carrying wheels arranged in a common plane, in combination with balancing apparatus comprising propeller blades revolvable in a horizontal plane and in a direction adapting them to exert a tendency to lift the body of said conveyance.
14. A conveyance provided with a single row of alined supports and with propeller blades revolving in laterally spaced planes at variable relative speeds for balancing said conveyance on said alined supports under the stress of an unbalanced lateral force.
15. A vehicle supported on a single row of points and provided with propeller blades revolvable about axes angularly adjustable in a vertical plane for producing combined propulsion and balancing effects, other blades revolvable in laterally-spaced vertical planes for compensating the centrifugal force and wind pressure on said vehicle.
16. A vehicle mounted on a single row of alined supports, air-whirling blades revolvable in laterally-spaced vertical planes, the blades revolving in one plane being operable in an opposite direction and at different relative speeds with respect to the planes revolving in the other plane for neutralizing the effects of centrifugal force on said vehicle; and a pivotally-mounted blade movable about an axis in a vertical plane.
17. A vehicle provided with a single row of alined supports and having oppositely-presented propellers on opposite sides thereof, said propellers being operable at relatively different speeds on a curve to produce a force toward the center of curvature for counteracting the centrifugal force on said vehicle due to the curve.
18. The combination with a vehicle pro-
- vided with a single row of alined supports, of motor-driven propellers presented forwardly and rearwardly on said vehicle, and other motor-driven propellers presented laterally in opposite directions on said vehicle, the last-mentioned propellers being operable at variable relative speeds.
19. A vehicle provided with a single row of carrying wheels arranged in a common plane, in combination with propeller blades for balancing said vehicle on said wheels, and a prime mover connected to one of said carrying wheels, said wheel constituting the rotating part of said motor.
20. In a device of the character described, the combination with a monorail support, of a vehicle, motors for said vehicle, said motors being provided with rotating parts forming vehicle wheels arranged in a common vertical plane, and propellers mounted on said vehicle, for balancing it on said monorail.
21. In a device of the character described, the combination with a monorail support, of a vehicle adapted to travel over said monorail support, a carrying wheel for said vehicle, said carrying wheel comprising relatively movable parts respectively provided with tread portions for accommodating differential movements along the inner and outer edges of a curved rail, and a motor for said vehicle, one of said relatively movable parts of the carrying wheel constituting a rotating part of said motor.
